UNITED STATES PATENT OFFICE.

CHRISTIAN WM. MEINECKE, OF JERSEY CITY, NEW JERSEY, ASSIGNOR TO
THE MEINECKE & COMPANY, OF NEW YORK, N. Y.

DESIGN FOR AN ICE OR HOT WATER BAG.

SPECIFICATION forming part of Design No. 33,913, dated January 15, 1901.

Application filed December 11, 1900. Serial No. 39,566. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for Ice or Hot Water Bags, of which the following is a specification.

This design consists in an ice or hot water bag of circular outline, with radiating lines, and having a centrally-located mouth with a threaded thimble, the latter having oppositely-extended top and bottom flanges.

The design is illustrated in the annexed drawings, in which—

Figure 1 is a plan view of the bag. Fig. 2 is a side elevation of Fig. 1.

The bag *a* is of circular or approximately circular outline, with radiating lines or creases

b on top. The mouth *c* is shown centrally located or in the middle of the top. The flanges extend in opposite directions. The upper flange projects outwardly and the lower flange inwardly.

The design gives a striking and characteristic appearance.

What I claim as new, and desire to secure by Letters Patent, is—

The design for an ice or hot water bag as herein shown and described.

In testimony whereof I have hereunto set my hand in the presence of the subscribing witnesses.

CHRISTIAN WM. MEINECKE.
